UNITED STATES PATENT OFFICE.

XIMENA W. SAUL, OF ROANOKE, VIRGINIA.

WINDOW-SHADE BRACKET.

Application filed September 19, 1921. Serial No. 501,562.

To all whom it may concern:

Be it known that I, XIMENA W. SAUL, a citizen of the United States, residing at Roanoke, in the county of Roanoke and 5 State of Virginia, have invented certain new and useful Improvements in Window-Shade Brackets, of which the following is a specification.

The present invention has to do with improvements in window shade brackets, and the object in view is to provide a simple article of manufacture that may readily be formed from a metal blank to provide a bearing support for the shade and a brace coacting with the support so as to maintain the same rigidly offsetting from the bracket body.

This and such other objects as may hereinafter appear are attained by the novel construction, combination and arrangement of parts to be hereinafter specifically described and claimed.

Reference will now be had to the accompanying drawings forming a part of this 25 specification, wherein:

Figure 1 is a fragmentary view of a window frame having my window brackets applied thereto in operative position.

Figure 2 is a front elevation of one of the 30 shade bracket supports.

Figure 3 is an end view of the same; and

Figure 4 is a view of the stamped blank from which the device is formed.

Throughout the following detailed description and on the several figures of the drawing, similar parts are referred to by like reference characters.

The bracket invention which forms the subject-matter of this application is designed to be constructed from a blank piece of metal of the shape which is best depicted in Figure 4 of the drawing, this being made of any suitable material and of any suitable size which may be required according to the 40 nature or size of the window shade with which it is to be employed. The body of the blank or its central portion 1 is provided with the necessary openings 2 by means of which the bracket is attached in position 45 upon a window frame. The central portion is cut with the lateral extension 3 which forms the shade-bearing support and this is

provided with the usual pintle opening or slot, depending upon whether the particular bracket is to serve for one or the other of the ends of the window shade.

The opposite side of the body 1 is formed with the lateral extension 4 which is bent along the line 5 outwardly and over into a position in which the extremity of the said portion 4 abuts against the bearing support 3 intermediate its length. The edge 6 of the lateral portion 4 is suitably beveled, preferably so as to lie flush against the face of this bearing support 3, and the contacting surfaces may be spot-welded or otherwise attached so as to make the bearing support quite rigid and capable of resisting distortion in use. By arranging this form of support the bracket may be made of rather 70 cheap material, if necessary, or desired, without in any wise sacrificing the strength of the shade bracket.

Obviously the particular configuration of the bracket may be modified and I do not 75 wish to be restricted as regards the character of the metal or the size which may be given to the article in the actual manufacture or construction of the device.

Having thus described my invention, what 80 I claim as new and desire to secure by Letters Patent is:

A window shade bracket of the type described consisting of a plate or body portion adapted to be fastened to a window 85 frame and having a vertically disposed shade-bearing support extending from one edge and a brace extending from the opposite edge into coacting relation to the bearing support, said bracket being formed from 90 a metal blank from the lateral edge of the body of which the shade-bearing support is bent outwardly at right angles and the brace is formed by bending the material from the opposite edge outwardly and over against 95 the shade-bearing support, said brace contacting with the outer face of the latter at a point intermediate its length so as to lie diagonally with respect to the body to brace the shade-bearing support against lateral 100 stresses outwardly thereagainst.

In testimony whereof I affix my signature.

XIMENA W. SAUL.
